ARTHUR FRIEDMAN, OF CLEVELAND, OHIO, ASSIGNOR TO THE CLEVELAND HEATER COMPANY, OF CLEVELAND, OHIO, A CORPORATION OF OHIO

COUPLING FOR CIRCULATING COILS

Application filed February 29, 1928. Serial No. 257,917.

This invention relates to improvements in gas fired liquid heaters and in particular to the circulating coils for gas burning domestic water heaters.

5 It has for its object the provision of a water heater circulating coil that is inexpensive and easy to manufacture, and that is more durable than the ordinary type of circulating coils, and that is protected against 10 the destructive action of the condensation products of combustion of the gaseous fuels used in gas burning water heaters.

15 My invention in general consists in the provision of an extending lip formed on the lower coupling and in contact with the under side of the lower portion of the heater coils, for the purpose of collecting and evaporating the condensation products of combustion from the gas burner.

20 The principal cause of failure in coils of this type is generally attributed to the presence of sulphuric acid in the water of condensation which collects on the coils and runs to their lowermost portion and there attacks 25 the joint between the coils and the coupling.

In copper water heater coils of the ordinary type, there is a decided tendency to failure at the point of the coils where they enter the lower coupling member. The failure results 30 from the disintegration of the copper, from which the coils are made. It is usually accompanied by the formation of copper sulphate at the point of failure of the coil. It is common knowledge that any commercial 35 gases particularly manufactured gas, upon burning give off sulphur dioxide, as well as water vapor.

The accepted theory of the operation of this phenomena in water heaters is that the 40 condensation of water vapor, which takes place on the heater coils, causes the formation of sulphurous acid by combining with the sulphur dioxide given off by the burning gas.

45 As the weak sulphurous acid thus formed on the heater coils runs to the bottom of the coils, a certain amount of it is converted into sulphuric acid, by reason of coming in contact with what copper oxide may be present on the 50 heater coils.

The acid solutions thus formed, collect at the lowermost point of the coils, which is where they enter the coil coupling. At this point there is apt to be present considerable copper oxide if it is a brazed joint. The 55 oxide referred to is present as a result of the action of the gas flame used in the brazing operation.

Furthermore, the copper tubing at the brazed joint is somewhat weakened, due to 60 the heat applied in brazing, which causes some oxidation as well as annealing, both of which are apt to leave this portion of the copper tubing in a condition in which it is more susceptible to the corrosive action of 65 sulphuric action than the other portions of the tube.

Disregarding for the moment, the type of joint between the tubing and the coupling, 70 whether it be a brazed joint or a union coupling, it is apparent that a part of the aforementioned liquids, condensed from the products of combustion of the gaseous fuel, come to rest at the junction of the coupling and the 75 coils.

At this junction point, which is in close proximity to the heater burner, the condensation products are further concentrated by direct action of the flange and evaporation of excess water in the acid solution producing concentrated sulphuric acid, which readily combines with the copper of the heater 80 coil.

It is upon this theory, which is supported 85 by the presence of copper sulphate at the junction of the coupling and the tubing, after the heater has been in use for some time, that the common cause of failure of the copper coils of water heaters is accounted for.

The formation of scale and liming of the 90 interior of the heater coils accelerates their deterioration. Under these conditions, when in operation, the heater coils are kept at a much higher degree of temperature, due to 95 the low thermal conductivity of the fouled tubing, and in addition to being more rapidly disintegrated by sulphuric acid, the coils are also oxidized by the direct action of the burner flame.

The primary object of this invention is to prevent the accumulation of the harmful condensation products of combustion at the weakest part of the heater coil.

5 This result is accomplished in my improved coil by the provision of a projecting lip which is integrally formed on the lower coil coupling member and which serves as a means for collecting and diverting the condensed liquids on the coil away from the joint between the coil and the coupling.

This invention is particularly useful in water heaters in which the ends of the circulating coils are brazed in the coil coupling member, as the coils are somewhat weakened by this operation, due to the high heat which is applied to them and to the action of fluxes which are used in brazing.

20 In the accompanying drawings: Fig. 1, illustrates a front elevation partly in section of a water heater constructed in accordance with and adapted for use in practicing my invention. Fig. 2, is a top elevation of the lower coupling member shown in Fig. 1. Fig. 25 3, is a side elevation of the lower coupling member. Fig. 4, is an elevation showing the under side of the lower coupling member and Fig. 5, is a section taken on line 5—5 Fig. 3.

Referring to Fig. 1, the reference numeral 30 1, indicates the heater casing or jacket of a conventional gas fired domestic water heater. This casing provides a housing for the copper water circulating coils 2 which are adapted to be put into communication with a storage 35 vessel or tank by means of the lower and upper union-connections 3 and 4, respectively.

40 Means for applying heat to the coils is provided for by the gas burner 5, which is mounted on an air and gas mixing tube 7, of the Venturi type. The burner 5 is positioned below the coils in the lower portion of the heater jacket. A gas cock 8 is mounted at the inlet end of the mixing tube 7, and is adapted to be connected to a source of gas 45 supply.

The lower ends of the coils 2 are adapted to be received in the coupling member 6. The usual method of securing the coils in this member is by brazing. A pair of outwardly 50 extending tapered lips 9 form a part of the coupling casting. These lips extend for a short distance along the underside of the heater coils 2 at the point where they enter the coupling member.

55 The purpose and object of the lips 9 is to provide a path for the liquids which are condensed from the products of combustion on the outside of the coil and which under the influence of gravity find their way to the 60 lower coupling member. The lips 9 tend to direct the condensation products away from the brazed joint between the coupling and the coils and cause them to accumulate and drip from the point 10 of the coupling member 6.

65 The corrosive action of whatever sulphuric

acid may be present in the afore-mentioned liquids is directed against the thick and heavy wall of the coupling casting instead of on the thinner wall of the tubing 2. In this manner the life of the coils is greatly lengthened by 70 protecting them at their weakest point from the corrosive action of the products of combustion from the gas burners, which products condense and collect on the heater coils.

It is apparent that my improved heater 75 coil could be used in conjunction with oil burning water heaters as well as gas burning water heaters and that it could be used to advantage in the heating of liquids other than water, where said coils are subjected to 80 treatment similar to that which they receive in gas fired water heaters.

Furthermore, it is to be understood that the 85 particular forms of apparatus shown and described, and that particular procedure set forth, are presented for purposes of explanation and illustration and that various modifications of said apparatus and procedure can be made without departing from my invention as defined in the appended claims: 90

Having described my invention, I claim:

1. A gas fired water heater comprising a heater casing, a circulating coil housed in said casing, a lower coupling member receiving said coil, means to apply heat to said coil, 95 and means integrally formed on said lower coupling member comprising an extending portion of decreasing thickness as its outer edge is approached and adapted for contact with said coil to direct the flow of the condensed products of combustion deposited on said coil from the joint between said coupling member and said coil.

2. In a gas fired water heater, water circulating coils, a lower coupling member connected to the corresponding ends of said coils, and a pair of tapered projecting lips integrally formed on said coupling member extending along and in contact with the under sides of said coils. 105

3. A coupling member for a water heater coil comprising, a single casting having an opening receiving an end of the coil and having formed thereon a narrow tapered extension contiguous to said opening adapted to 115 extend along and in contact with the under side of the heater coil.

In testimony whereof I affix my signature:

ARTHUR FRIEDMAN.
